UNITED STATES PATENT OFFICE.

JOHN MITCHELL AND JOHN CECIL GEORGE COSSEY, OF LONDON, ENGLAND.

COUPLING FOR RAILWAY AND LIKE VEHICLES.

Application filed July 31, 1922. Serial No. 578,730.

To all whom it may concern:

Be it known that we, JOHN MITCHELL and JOHN CECIL GEORGE COSSEY, both subjects of the King of Great Britain, residing in London, England, have jointly invented certain new and useful Improvements Relating to Couplings for Railway and like Vehicles, of which the following is a specification.

The invention relates to the known type of central couplings for railway and like vehicles in which a separate member provided between the coupler head and the drawbar forms with these parts a universal joint allowing deflections in two planes 15 mutually at right angles.

According to the invention a ferrule or the like surrounding one end of the separate member transmits the buffing stresses to the buffing spring and relieves the drawbar, which slides in the ferrule or its equivalent, of these stresses. The ferrule is inserted in the headstock or in a box member secured to the longitudinals or headstock or to both longitudinals and headstock, the intermediate member being so formed that relative rotation between the coupler head and drawbar is prevented. The intermediate member may consist of a block with two pins at right angles to each other, one of which engages in a bearing in the coupler head and the other in a bearing in the drawbar, or conversely the pins may be secured respectively to the coupler head and drawbar and the bearings provided in the block. 35 Either of the pins may be replaced by a pair of pins placed on either side of the longitudinal axis.

The head is centralized in the known manner by one or more bearing surfaces provided at the rear of the coupler head and pressed by a main or main and subsidiary spring against a ferrule which is guided in the headstock and serves as a guide for the drawbar.

45 A single spring may be employed to centralize the coupler head and also to transmit the buffing and drawing stresses, the forward end of the spring abutting against the rear of the ferrule and the rearward end against a guided abutment capable of forward movement.

This spring may be replaced by a main and subsidiary spring, the latter having a limited range and serving to assist to centralize the coupler head, to absorb light draft stresses and to take up the wear on all work-

ing parts between the coupler head and the drawbar.

The subsidiary spring, which may be placed in tandem or concentric with the main spring, is connected with the latter through a ferrule so arranged that, while draft stresses are initially taken up by the two springs in series, the buffing stresses are taken only by the main spring.

60 In the accompanying drawings which illustrate examples of constructions according to the invention,

Figure 1 is a longitudinal vertical section taken through a coupling constructed according to the present invention.

Figure 1^a is a plan view of the intermediate member of the coupling.

Figure 1^b is a section taken through the same substantially on the line 1^b—1^b of Figure 1.

Figure 1^c is a side elevation of a slightly modified form of box and support of the coupling, showing the support external to the box.

Figure 2 is a sectional plan view of a portion of the coupling, showing a modification of the universal joint member.

Figure 3 is a fragmentary sectional elevation showing another modification of the intermediate member.

Figure 4 shows a vertical section taken lengthwise through the intermediate portion of the coupling showing a further modification.

Figure 4^a is a horizontal section taken through the same.

Figure 5 is a horizontal section taken through a still further modified form of the coupling.

Figure 6 is a similar section taken at substantially right angles to Figure 5 and showing a further slightly modified form of the invention.

Figure 6^a is a detailed plan view of the intermediate member of Figures 5 and 6.

Similar parts are denoted by the same reference letters in all the figures.

Referring to Fig. 1, A is a buffer or coupler head, B the headstock, C the drawbar; D is a buffing and draw spring surrounding the shank of the drawbar, E a plate secured to the headstock or frame and connected by side plates *b'* with an end plate *b* to form a rectangular box or casing. F is an intermediate member forming a universal joint with the drawbar and the head. Fig. 1^a is a plan

view of this member. A relatively light spring G abuts against a ferrule H which surrounds the reduced end c of the drawbar, the flange h of the ferrule forming an abutment for one end of the buffering spring D. The ferrule H slides in a split bush K inserted in the plate E. The two halves of the bush K are held together by bolts and nuts k and the bush is secured to the plate E by bolts k^2 as shown in Fig. 1^b. The reduced end of the drawbar is screw-threaded, a ferrule I on the bar forming an abutment for the other end of the spring G and being secured in position by a nut J.

15 The buffer head A is recessed at a to conform to the circular section of the end of the member F. L is a horizontal pin secured to the buffer head and about which the intermediate member F and the buffer head A can move in a vertical plane. If a greater centralizing effect is required in one direction, for example to support the weight of the buffer head, the pin L may be displaced from the central axis. M is a vertical pin secured to the intermediate member F and passing through a hole in the end c' of the drawbar; this pin allows of suitable relative movement in a horizontal plane between the drawbar C and the buffer head A.

30 The portion c^2 of the drawbar forms an enlarged head adapted to slide in a sleeve or ferrule N; the sleeve N is adapted to slide in a rectangular portion of the casing. By this construction the end of the drawbar is directly supported in the vertical and horizontal planes by the sleeve N which is itself supported in the fixed casing O, so that the drawbar is entirely freed from bending stresses. The main spring D and the subsidiary spring G support the coupler head A and take up the initial draft stress on the head; further draft and all buffering stresses are taken up by the spring D.

45 Rotation of the head is prevented by the rectangular section of the intermediate member F and the rectangular section of the drawbar C.

In the construction shown in Fig. 1, the support O in which the sleeve N slides is integral with the end b of the box and within the latter. This box can be easily inserted into existing vehicles at small cost and helps the under frame to resist the heavy buffering and drawing stresses due to the great weight and length of modern trains.

In Fig. 1^c the support O is external to the box.

60 In the usual known method in which a detachable plate is secured to the longitudinals or headstock by nuts and bolts, there is considerable danger of the bolts becoming loose under these severe stresses.

In the arrangement shown the spring D is inserted with the ferrule H without initial compression and the split bush K is inserted

from underneath the vehicle between the knee E and the flange h , when the spring D has been compressed by screwing up the nut J.

In the example shown in Fig. 2, the intermediate member F' is somewhat differently constructed and the head c^2 of the drawbar is modified correspondingly, also the pin L in the head A' and the pin M in the drawbar C' are at right angles to the similar pins shown in Fig. 1.

75 In the example shown in Fig. 3, rotation in the vertical plane of the member F² is effected about two horizontal pins L', L² secured to the buffer head A², the member F² connecting the head and the drawbar C' being provided with elongated holes engaging with and accommodating the pins L' and L². The vertical pin M in the head c^3 of the drawbar C' passes through a hole in the other extremity of the member F² and slides in a sleeve N of rectangular cross section.

80 In this construction when a pivoting movement occurs only one of the pair of parallel bearings is operative; this arrangement increases the centralizing effect of the spring pressure. If a greater centralizing effect is required in one direction, for example to support the weight of the buffer head, one pin may be placed at a greater distance from the central axis.

85 In the example shown in Figs. 4 and 4^a vertical pins M' and M² in the head c^4 of the drawbar C² pass through elongated holes provided in the intermediate member F³. In other respects the construction is similar to that shown in Fig. 3.

90 In the example shown in Fig. 5, the intermediate member F and the pins L and M are similar to that shown in Fig. 1, except that they are turned through 90° respectively. In this construction the parts b and E are not connected by side plates and the casing O is secured to the headstock B.

100 In the example shown in Fig. 6 the intermediate member F is arranged as in Fig. 1, but the pins L and M are interchangeable and corresponding slight alterations are made in the form of the intermediate member F.

110 Having thus described the nature of the said invention and the best means we know of carrying the same into practical effect, we claim:—

115 1. In a central coupling for railway and like vehicles, a coupler head, a draw bar, an intermediate member interposed between said coupler head and said draw bar, and means provided in said member to allow relative deflection in two planes mutually at right angles between the coupler head and the draw bar, a casing, front and rear ferrules adapted to slide in said casing, a draft and buffering spring inserted between said ferrules, said front ferrule surrounding one end of said intermediate member and form-

ing a guide for said draw bar and abutting against said coupler head said rear ferrule forming a guide for said draw bar and an abutment for said spring.

5 2. In a central coupling for railway and like vehicles, a coupler head, a draw bar, an intermediate member interposed between said coupler head and said draw bar, a pin at the rear end of said member pivotally connected with the front end of the draw bar, a pin at the front end of said member at right angles to said first mentioned pin and pivotally connected with said coupler head, a casing, front and rear ferrules adapted to slide in said casing, a draft and buffing spring inserted between said ferrules, said front ferrule surrounding one end of said intermediate member and forming a guide for said draw bar and abutting against said coupler head said rear ferrule forming a guide for said draw bar and an abutment for said spring.

3. In a central coupling for railway and like vehicles, a coupler head, a draw bar, an intermediate member interposed between said coupler head and said draw bar, a pin at the rear end of said member pivotally connected with the front end of the draw bar, a pin at the front end of said member at right angles to said first mentioned pin and pivotally connected with said coupler head, a casing, front and rear ferrules adapted to slide in said casing, a draft and buffing spring inserted between said ferrules, said front ferrule surrounding one end of said intermediate member and abutting against said coupler head, the enlarged front end of said draw bar of rectangular cross section being guided in said front ferrule said rear ferrule forming a guide for said draw bar and an abutment for said spring.

4. In a central coupling for railway and like vehicles, a coupler head, a draw bar, an intermediate member interposed between said coupler head and said draw bar and means provided in said member to allow relative deflection in two planes mutually at right angles between the coupler head and the draw bar, a casing, front and rear ferrules adapted to slide in said casing,

a draft and buffing spring inserted between said ferrules, said front ferrule surrounding one end of said intermediate member and forming a guide for said draw bar and abutting against said coupler head which is recessed to enclose the front end of said intermediate member said rear ferrule forming a guide for said draw bar and an abutment for said spring.

5. In a central coupling for railway and like vehicles, a coupler head, a draw bar, an intermediate member interposed between said coupler head and said draw bar, a pin at the rear end of said member pivotally connected with the front end of the draw bar, a pin at the front end of said member at right angles to said first mentioned pin and pivotally connected with said coupler head, a casing, front and rear ferrules adapted to slide in said casing, a draft and buffing spring surrounding one end of said intermediate member and forming a guide for said draw bar and abutting against said coupler head which is recessed to enclose the front end of said intermediate member said rear ferrule forming a guide for said draw bar and an abutment for said spring.

6. In a central coupling for railway and like vehicles, a coupler head, a draw bar, a member interposed between said coupler head and said draw bar, a pin at the rear end of said member pivotally connected with the front end of the draw bar, a pin at the front end of said member at right angles to said first mentioned pin pivotally connected with said coupler head, plates secured to said vehicles, supports secured to said plates, ferrules sliding in said supports and forming guides for said draw bar, a draft and buffing spring abutting against the inner ends of said ferrules, and an auxiliary spring surrounding the rear end of the draw bar and abutting against the rear end of the rear ferrule and an abutment on the rear end of the draw-bar engaging the auxiliary spring.

In testimony whereof we have signed our names to this specification.

JOHN MITCHELL.

JOHN CECIL GEORGE COSSEY.
